(57) **CLAIM**

The ornamental design for a garment, as shown and described.

DESCRIPTION

FIG. 1 is a front view of a garment in a laid-flat configuration;

FIG. 2 is a front view of the garment of FIG. 1, in a second configuration in which the pocket is revealed;

FIG. 3 is a front, right, lower perspective view of FIG. 1; FIG. 4 is a front, right, lower perspective view of FIG. 2; FIG. 5 is a front view of a second garment that is in a laid-flat configuration, showing the design of FIG. 1; and,

FIG. 6 is a front view of a third garment that is in a laid-flat configuration, showing the design of FIG. 1.

The evenly spaced broken lines shown in the drawings are directed to environment, are for informational purposes only, and form no part of the claimed design

The long and short broken lines are boundary lines, which define bounds of the claimed design. These boundaries do not exist in reality in the article embodying the design. It is understood that the claimed design extends to these boundaries but does not include the boundaries.

The surface shading on the claimed portion is provided only to indicate the character and/or any contour or curvature of the surfaces. It does not indicate color, texture, markings that actually exist thereon, indicia, graphic representations, surface treatment, or any other ornamentation applied to the article.
